United States Patent Office

Des. 176,964
Patented Feb. 21, 1956

176,964

TRUCK

William L. McCullough, Lehighton, Pa.

Application October 6, 1953, Serial No. 27,091

Term of patent 14 years

(Cl. D14—3)

Fig. 1.

Fig. 2.

Fig. 3.

Fig. 1 is a side elevation of a truck showing my new design;

Fig. 2 is a front perspective view of the same; and Fig. 3 is a rear perspective view of the same.

I claim:

The ornamental design for a truck, as shown.
